DESIGN FOR A COMBINED TRAILER AND CANOPY

Thurlow E. McFall, Sparta, Mich.

Application May 20, 1935, Serial No. 56,917

Term of patent 14 years

To all whom it may concern:

Be it known that I, Thurlow E. McFall, a citizen of the United States, residing at Sparta, in the county of Kent and State of Michigan, have invented a new, original, and ornamental Design for a Combined Trailer and Canopy, of which the following is a specification, reference being had to the accompanying drawing, forming part thereof.

In the drawing:

Fig. 1 is a side elevation of the combined trailer and canopy.

Fig. 2 is a front end elevation thereof.

Fig. 3 is a rear end elevation, and

Fig. 4 is a plan looking down upon the canopy in reduced size.

The dominant feature of my design resides in the canopy portion shown in solid black lines.

I claim:

The ornamental design for a combined trailer and canopy, substantially as shown and described.

THURLOW E. McFALL.
